F. J. RAVLIN,
COMBINED PLUG SWITCH AND FUSE.
APPLICATION FILED JAN. 26, 1914.

1,121,288.

Patented Dec. 15, 1914.

UNITED STATES PATENT OFFICE.

FREDERICK J. RAVLIN, OF CHICAGO, ILLINOIS.

COMBINED PLUG-SWITCH AND FUSE.

1,121,288.

Specification of Letters Patent. Patented Dec. 15, 1914.

Application filed January 26, 1914. Serial No. 314,321.

To all whom it may concern:

Be it known that I, FREDERICK J. RAVLIN, a citizen of the United States, residing at Chicago, in the county of Cook and State of Illinois, have invented certain new and useful Improvements in Combined Plug-Switches and Fuses, of which the following is a specification.

My invention has for one of its objects to provide a combined plug switch and fuse especially adapted for heavy service, in which the electrical appliances employed are adequately protected against the weather, and are suitable for installation in railway yards, and other places where the appliances are subject to rough usage and adverse weather conditions, without danger of breakage, deterioration of its mechanical parts, or injury to its electrical connections.

Further my invention has for its object to provide a construction, suitable for general use where such electrical appliances are needed, which is simple, cheap, easily manufactured, readily installed, and durable and efficient in operation.

In the drawings wherein I have illustrated a commercial embodiment of my invention Figure 1 is a front view, with parts broken away to show the internal construction of the appliance; Fig. 2 is a vertical section on line 2—2 of Fig. 1 with the plug omitted; Fig. 3 is a cross section on line 3—3 of Fig. 1; Fig. 4 is an end view of the casing; and Fig. 5 is an enlarged detail with parts broken away of an insulating block and contact.

In the construction specifically shown in the drawings, the casing generally indicated at 10 comprises a back plate 11 and a front housing 12. The housing 12 is preferably of rectangular form in plan, provided at its corners with posts 13 against the bottoms of which the back plate 11 bears, said posts receiving screws 14 which extend through the corners of the base plate so that when the parts are assembled the outer or back wall of the base plate lies flush with the edges of the housing as shown in Fig. 3. The housing has in appropriate positions thereon lateral ears 14' for the reception of screws or bolts 15 to attach the structure to a suitable support, generally a vertical wall.

The front wall of the housing 12 has formed in its upper portion a large opening 16 surrounded by a lip 17 and for the closure of this opening I provide a closure plate 18

constructed to fit neatly within the lip or rim 17, the plate being hinged as at 19, beyond the plane of the rim 17, to suitable ears on the front wall, and being provided with a finger piece 20 so that it may readily be swung to open or closed position. The lower portion of the front wall is inclined away from the back plate as shown at 21, said inclined wall 21 meeting, preferably at right angles, the bottom wall 22 in which is formed an opening 23 extending clear to the edge of the housing, and at its top preferably formed in a reentrant angle, as at 23'.

The back plate 11 has a sill or bar 24 thereon entering the opening 23, said sill being preferably of the same depth as the added depth of the casing-end due to the inclination of wall 21, and the sill having thereon a lip 25 at its front edge, coacting with the bottom wall in defining the bottom orifice.

Within the casing the back-plate 11 has a shallow projecting transverse rib 26 in position substantially alining with the upper end 30 of front wall-portion 21, to act as an abutment for the contact base, and paralleling its sides said back plate carries two wings 27 constituting lateral abutments for the contact base.

The insulating base, 30, which carries the switch contacts, is made in two duplicate blocks 31, meeting in a central longitudinal plane vertical to the back wall.

Jointly the blocks 31 provide an end-opening recess 32, similar in shape to the casing orifice, the recess being surrounded, at its mouth, by a lip 34 which projects through the opening 23 of the casing. Externally the base fits neatly between the wall 21 on the front, and the sill 24 and base plate 11 at the back, resting in inclined position paralleling the front wall 21, with its lower end abutting against the bottom wall 22 and lip 25, and its upper end stopped 100 against abutment rib 26.

The lateral side-walls of the base-sections carry spring-leaf contacts, with connections running therefrom to the exterior of the blocks. Each lateral side wall is grooved 105 as at 36 from its upper end nearly to its lower end, and the inner face of each said wall has a recess 37 near its lower end. Each spring contact-leaf 39 has its end doubled back as at 40, and the end 40, lying 110 in the recess 37, is anchored by a nut 41 on a screw 42 passing through the wall and

engaging a contact plate 43, seated in groove 36, said contact plate bearing a binding screw 44 from which an insulated wire 45 leads upward in the groove 36. I prefer that the lateral abutment wings 27 be spaced apart somewhat farther than the width of the base, and that insulating strips 46, of fiber or the like, long enough to overlie the plate 43 be forced between the wings and the sides of the base, binding the sections of the latter against lateral separation.

The coacting plug 50, preferably made of wood, bakelite, or the like, has a tubular handle 51, and a blade 52, with one angular face, shaped to interfit in the recess of the base. One wall of the base recess is angled to coact with the angular face of the plug so that the blade will go into the base recess only in one position, and the polarity of the external connections cannot be reversed accidentally. The blade carries on its sides contact plates 53, connected with suitable wiring leading through the hollow handle.

Within the upper portion of the casing I provide a fuse structure. The insulating base 60 therefor is mounted on a fiber sheet 61 and secured to the back wall 11 by screws 62. The fuse plug terminals 63 are secured in pairs to the base 60, and carry the fuses 64, located under the opening 16. The binding posts of the fuse terminals are connected respectively with wires 45, leading to the switch contacts, and with wires 45' leading through a bushed aperture 65 to the exterior of the structure for connection with the mains.

It will be observed that in use the plug is presented to the socket at an angle to the back-wall of the receptacle, so that while the receptacle is shallow, as adapted to be applied to a vertical wall or post, and has its orifice at the bottom, protected from the elements, the plug may easily be inserted without bringing the hand of the operator into contact with the supporting wall. The construction permits easy assemblage of the contact springs and wiring connections with the halves of the socket base, and the half-sections are easily assembled on the back plate and connected to the fuse members before the casing sections are secured together, and when the assemblage is completed the socket sections are firmly positioned against displacement in any direction. The fuse structure is positioned for advantageous connection with the socket, is separately detachable, is accessible for renewal of fuses, and has its incasing portion adequately weather proofed by the snug fitting, gravity-closed cover plate which may however be instantly opened.

While I have herein described in some detail an embodiment of my invention, it will be apparent to those skilled in the art that

changes in structural details may be made without departure from the spirit of my invention and within the scope of the appended claims.

What I claim is:—

1. In a structure of the character described, a receptacle casing having a back plate and a front wall with its lower portion inclined outwardly from the back plate, there being an opening in the upper portion of front wall, and an opening in the bottom of the casing, a closure for the front opening, a fuse structure within the casing accessible through the front opening, and a socket in the lower portion accessible through said bottom opening, said socket disposed in parallelism to the angular portion of the casing wall, and said socket and fuse member electrically connected within the casing.

2. In a structure of the character described, the combination of a casing comprising a back plate, a shallow front housing interfitting therewith and attached thereto, said housing having its front wall outwardly inclined at its lower portion and having a bottom orifice, and a front orifice above the inclined portion, a gravity closing cover for the front orifice, a sill on the back plate, at its lower end, a projection on the back plate between its ends, a socket structure fitting between the back plate and housing, resting in inclined position on said sill and abutting against said projection, said socket having its opening registering with the bottom opening of the casing, and a fuse structure, electrically connected with said socket positioned in the casing above said projection for access through the front opening.

3. In a device of the character described, the combination of a back plate having longitudinal wings, a bottom sill and a transverse rib, a front housing having a front wall outwardly inclined toward its bottom and having a bottom wall with an orifice therein, a two piece insulating base divided longitudinally in a vertical plane, positioned by the sill, rib and front wall, to lie at an inclination to the back-plate, said insulating base having a socket therein opening to the bottom orifice, and filler members between the base and the longitudinal wings, positioning said base-sections against lateral separation.

4. In a structure, of the character described, the combination of a receptacle having its front and rear walls parallel throughout their upper portions, and divergent toward their bottom, said receptacle having a front orifice in its upper portion, and a bottom orifice, an insulating base within the upper portion of the receptacle, fuse members thereon accessible through the front orifice, a closure for said orifice, a

6 plug-socket within said receptacle opening to the bottom orifice and paralleling the inclined front wall-portion, said plug socket being positioned entirely below the front
6 orifice and electrical connections between said socket and the fuse members.

5. In a structure of the character described, the combination of a receptacle having an upper and a lower chamber, the lower
10 chamber being closed at its front face, a front orifice in the upper chamber and a bottom orifice in the lower chamber, a closure for said front orifice, a fuse structure within the upper chamber opposite the
15 front opening, and a plug socket in the lower chamber electrically connected to said fuse structure, opening to the bottom orifice.

6. In a device of the character described, the combination of a back plate having longitudinal wings, a bottom sill and a transverse rib, a front housing having a bottom wall with an orifice therein, a two piece insulating base divided longitudinally in a vertical plane, positioned by the sill, rib and
20 front wall, said insulating base having a socket therein opening to the bottom orifice, and filler members between the base and the longitudinal wings, positioning said base against lateral separation.

7. In a device of the character described,

the combination of a back plate having longitudinal wings, a bottom sill and a transverse rib, a front housing having a front wall outwardly inclined toward its bottom and having a bottom wall with an orifice 35 therein, and a two piece insulating base divided longitudinally in a vertical plane, positioned by the sill, rib and front wall, to lie at an inclination to the back plate, said insulating base having a socket therein opening to the bottom orifice.

8. In a device of the character described, the combination of a back plate having longitudinal wings, a bottom sill and a transverse rib, a front housing having a front wall outwardly inclined toward its bottom and having a bottom wall with an orifice 40 therein, an insulating base positioned by the sill, rib and front wall, to lie at an inclination to the back plate, said insulating base having a socket therein opening to the bottom orifice, and filler members between the base and the longitudinal wings, positioning said base against lateral movement.

In testimony whereof I hereunto set my hand in the presence of two witnesses.

FREDERICK J. RAVLIN.

In the presence of—

FORÉE BAIN,

MARY F. ALLEN.
